UNITED STATES PATENT OFFICE.

EDWARD F. GREENE, OF NEW YORK, N. Y., ASSIGNOR TO REVERE RUBBER COMPANY, OF CHELSEA, MASSACHUSETTS, A CORPORATION OF RHODE ISLAND.

DESIGN FOR A COMBINED SOLE AND HEEL.

Application filed January 21, 1928. Serial No. 24,969. Term of patent 14 years.

To all whom it may concern:

Be it known that I, EDWARD F. GREENE, a citizen of the United States, residing at New York, county and State of New York, have invented a new, original, and ornamental Design for a Combined Sole and Heel, of which the following is a specification, reference being had to the accompanying drawing, forming part thereof.

Fig. 1 is a plan view of a combined sole and heel showing my new design; Fig. 2 is a longitudinal cross sectional view on line 2—2 of Fig. 1.

I claim:

The ornamental design for a combined sole and heel, as shown.

Signed at New York, in the county of New York, and State of New York, this 20th day of January, 1928.

EDWARD F. GREENE.
